UNITED STATES PATENT OFFICE.

JACOB ROTHLSBERGER, OF MUNCIE, INDIANA, ASSIGNOR TO W. D. SMITH SILVER CO.,
A CORPORATION OF DELAWARE.

DESIGN FOR A SPOON, FORK, OR SIMILAR ARTICLE.

47,760.

Specification for Design. Patented Aug. 24, 1915.

Application filed April 14, 1915. Serial No. 21,475. Term of patent 14 years.

To all whom it may concern:

Be it known that I, JACOB ROTHLSBERGER, a citizen of the United States of America, and a resident of Muncie, in the county of Delaware and State of Indiana, have invented a new, original, and ornamental Design for Spoons, Forks, or Similar Articles, of which the following is a specification, reference being had to the accompanying drawings, forming part thereof.

Figure 1 is a front view of a spoon showing the improved design, tines of a fork

being represented in dotted outline. Fig. 2 is a side view of the same. Fig. 3 is a back view of the same. Fig. 4 is a cross-sectional view of the handle taken with the upper end thereof.

I claim:

The ornamental design for a spoon, fork, or similar article as shown.

JACOB ROTHLSBERGER.

Witnesses:

WILLIAM F. GORTON,
LEO. S. GUNTER.
